Inventor
Frank A. Fouts

UNITED STATES PATENT OFFICE.

FRANK A. FOUTS, OF WASHINGTON, DISTRICT OF COLUMBIA.

CIGAR-HOLDER.

SPECIFICATION forming part of Letters Patent No. 364,504, dated June 7, 1887.

Application filed April 9, 1887. Serial No. 234,215. (No model.)

To all whom it may concern:

Be it known that I, FRANK A. FOUTS, a citizen of the United States, residing at Washington, in the District of Columbia, have invented 5 certain new and useful Improvements in Cigar-Holders; and I do declare the following to be a full, clear, and exact description of the invention, such as will enable others skilled in the art to which it appertains to make and use 10 the same, reference being had to the accompanying drawings, and to the letters and figures of reference marked thereon, which form a part of this specification.

My invention is a cigar-holder. It consists 15 in the device which will be hereinafter described, and the improvement pointed out in the claims.

The objects of the invention are to enable one to smoke a cigar down to an exceedingly 20 small point without the necessity of handling 25 the cigar with the fingers, and obviate the danger of burning one's mustache or lips, and thereby serve as a bearing, guard, protector, or shield, and at the same time permitting the 30 exposure of the butt-end of the cigar back of the holder, so as to enable the smoker to enjoy the benefit of the weed to the fullest desirable extent.

Another object is to enable one to lay a 35 partly smoked cigar on any material without liability of injury, by burning, to said material.

Another object is the production of a cigar-holder which can be conveniently carried in the pocket, and which may be manufactured at 40 a cost so small that one (holder) may be furnished with each cigar by the manufacturer or dealer without additional cost to the consumer.

When the cigar is placed in the holder, said cigar is virtually provided with a flange, the 45 body of the holder constituting said flange. This flange, being interposed between the butt and fire end of a cigar, protects the lips or mustache, as stated, and permits the cigar to be consumed down to the outer face of the 50 flange. By this means a considerable portion of a cigar may be consumed which ordinarily is thrown away and wasted.

Stiff sheet-paper or card-board is preferably employed in the manufacture of the article. 55 In order that the holder may be stiffened and strengthened, I press a circumferential groove

in the body of the paper, and also form a groove in the handle, which communicates with the groove in the body. The groove in one side forms a corresponding rib on the opposite side 55 of the paper. These ribs serve to strengthen the device and permit the use of comparatively thin card-board in the manufacture of the holder. There are other materials, however, besides paper which may be employed in 60 the manufacture of the article.

In the accompanying drawings, Figure 1 represents a plan view of the holder. Fig. 2 is a central longitudinal sectional view taken on the line xx of Fig. 1. Fig. 3 represents a 65 perspective view of the holder and a partly-smoked cigar therein, both resting on a flat surface, the fire end of the cigar being elevated above said surface. Fig. 4 indicates a perspective view of the holder. Fig. 5 indicates a 70 edge view of the holder, having a partly-smoked cigar in position and a hand clasping the handle of the holder between the thumb and forefinger.

The body of the holder is indicated by the 75 letter A.

B represents a lateral projection or handle formed integral with the body A. Said body is also provided with a central opening, C, for the reception of the butt-end of a cigar. 80

The letter D indicates a series of projections formed integral with the body A, around the edge of the central opening aforesaid.

The letter E represents a circumferential rib on the body of the holder, and E' a rib on the handle. These ribs are formed by grooves on the opposite sides of the holder. The ribs serve to impart strength to the holder. The projections D are preferably made in spur form, as shown, so as to firmly retain the cigar 90 when placed in the opening. These spurs normally converge toward the center of the opening, as shown in Fig. 1. Said spurs, being formed of material more or less springy, readily yield and turn outward when the butt-end of a cigar 95 is inserted into the opening. The spurs, as hereinbefore stated, serve to retain the cigar within the holder, and they at the same time tend to hold the cigar in a line at right angles to the plane of the holder. This is effected by 100 reason of the fact that when the spurs are pressed outward they engage the cigar and

serve as a rest and support therefor. A single spur might answer the purpose; but a series is preferred. If but a single spur were used, the cigar would have a bearing on the point of the 5 spur and on the sides of the opening opposite said spur. Another and perhaps the principal advantage of the spurs is, that cigars of various diameters may be retained in the same holder. When a cigar is inserted into the opening in the holder, said cigar immediately encounters the points of the spurs. The spurs yield as the cigar is inserted and seated, and the points and outer portions of said spurs engage and secure the cigar irrespective of the 15 diameter thereof.

By means of the handle B one is enabled to manipulate the holder and cigar without danger of burning one's fingers.

I do not claim in this application a cigar, 20 as an article of manufacture, provided with a flange, plate, or shield permanently attached to or around its body, nor a cigar provided with a flange, plate, or shield permanently secured to its body, said flange, plate, or shield 25 having a handle, and I hereby make disclaimer thereto. The matter herein disclaimed is made the subject of an application for Letters Patent of the United States, filed May 23, 1887, Serial No. 239,034.

Having thus described my invention, I claim 30 as new and desire to secure by Letters Patent of the United States—

1. As an article of manufacture, a cigar-holder consisting of a plate or sheet provided 35 with an opening for the reception of a cigar, and with means located at the edge of said opening for engaging and securing the cigar, the opening aforesaid being so located that bearing portions or surfaces are left on the 40 sides thereof, substantially as described.

2. As an article of manufacture, a cigar-

holder consisting of a plate or sheet provided with an opening for the reception of a cigar, and with yielding means located at the edge of the opening, adapted to engage and secure a 45 cigar, the opening aforesaid being so located that bearing portions or surfaces are left on the sides thereof, substantially as described, and for the purposes set forth.

3. As an article of manufacture, a cigar-holder consisting of a plate or sheet provided with an opening for the reception of a cigar and one or more spurs for engaging and securing a cigar in the opening aforesaid, said opening being so located that bearing portions 55 or surfaces are left on the sides thereof, substantially as described.

4. As an article of manufacture, a cigar-holder consisting of a plate or sheet having a handle, said plate or sheet being provided 60 with an opening for the reception of a cigar and projections for engaging and securing a cigar in the opening aforesaid, said opening being so located that bearing portions or surfaces are left on the sides thereof, substantially 65 as described, and for the purposes set forth.

5. As an article of manufacture, a cigar-holder consisting of a plate or sheet provided with an opening for the reception of a cigar, and with means located at the edge of the opening for engaging and securing a cigar in said opening, the opening aforesaid being so located that bearing portions or surfaces are left on the sides thereof, said plate or sheet being also provided with a rib or bead, substantially as 70 specified.

In testimony whereof I affix my signature in presence of two witnesses.
